SPRING BUFFER

Harold E. Abkowitz, Pittsburgh, Pa., assignor to
 Pressed Steel Car Company, Inc., Pittsburgh,
 Pa., a corporation of Pennsylvania

Application August 19, 1938, Serial No. 225,702

4 Claims. (Cl. 213—9)

This invention pertains to mine cars and specifically to spring buffers for said cars and has for an object the provision of means resiliently cushioning the buffing and draft shocks imposed upon the car through the buffer.

In the drawing forming part of this specification, of which Fig. 1 shows in plan the buffer of the invention assembled on a car and Figs. 2 to 4 inclusive show sections taken on the lines 10 2—2, 3—3 and 4—4 respectively of Fig. 1, reference character 1 indicates a portion of a mine car having a floor sheet 2 and longitudinally extending sills 3. The buffer comprises a housing 4 which is rigidly secured to the floor and sills 15 of the car and extends outwardly therefrom, and a buffing block 5 mounted upon the housing and movable relative thereto longitudinally of the car to absorb buffing and draft shocks.

The buffer housing 4 comprises an end wall 20 6 extending upwardly from the plane of the floor 2 of the car and provided with rearwardly extending side flanges 7 having apertures therein to receive suitable fastening means for securing the housing to the sills 3. Adjacent the 25 base of the wall 6 and extending between the flanges 7 is a flange 8 having suitable apertures to secure this flange to the floor 2 of the car. Extending outwardly from the wall 6 and away 30 from the car on opposite sides of the longitudinal medial line through the car are spring housings comprising side walls 9 and 10 and an end closing wall 11. Connecting the spring housings and extending across the top thereof is a 35 top wall 12 extending to the buffer housing wall 6 and connected therewith. Between the spring housings the wall 12 is offset to permit the movement of the coupling pin as hereinafter described.

At least between the spring housings a bottom 40 wall 13 on the buffer housing 4 extends outwardly from the housing end wall 6, which bottom wall 13 is suitably shortened to permit movement of the coupling pin as hereinafter described.

As thus described the spring housing side walls 45 are connected across their top and are open at the bottom for insertion of the springs. Extending inwardly of the housing from the inner face 50 of each housing side wall are vertically disposed abutment walls 14 of a width less than one-half the transverse width of the spring housings. Extending from adjacent the free edge of the flanges 14 to the respective side walls 9 and 10 55 are substantially triangular flanges 15. In the

top wall 12 of the spring housings are suitable apertures 16 extending from the abutment walls 14 to adjacent the end walls 11 of the spring housing.

Disposed within each spring housing is a compression spring 32 having a spring cap at each end, one spring cap 17 being disposed against the walls 14 and the other spring cap 18 disposed against the wall 11. These springs and caps are inserted through the bottom opening 10 in the spring housing and each spring is preferably under an initial compression sufficient to retain the spring and caps within the housing. To assist in retention of the rear spring cap it is supported upon the flanges 15.

The buffer block comprises a front face 19, a top wall 20, and a bottom wall 21, with connecting side walls 22. The side walls being spaced apart a greater distance than the walls 10 of the spring housings and these walls 10 20 are preferably provided with outwardly extending bearing portions 23 lying adjacent the side walls so as to position the buffing block in a direction transversely of the car. The top and bottom walls of the buffer enclose the top and 25 bottom walls of the housing 4 which latter walls along with the spring housings provide a support for the buffing block.

At the longitudinal medial line through the car and extending on opposite sides thereof above 30 the top wall 20 of the buffing block is a coupling link housing comprising vertically disposed side and end wall 24 and a connecting top wall 25 in spaced relation to the wall 20. The coupling link housing top wall and top and bottom walls 35 of the buffing block are provided with suitably aligned apertures 26 for reception of a coupling pin 27 and the front face 19 of the buffing block has a suitable aperture 28 therein for reception of a coupling link to be engaged by this coupling pin 27. Spaced on opposite sides of the longitudinal medial line through the car are spring cap bearing members 30 on the inner face of the front wall 19 and extending toward the car, the walls 11 of the spring housings and the adjacent spring cap 18 having suitably aligned 40 apertures therein for reception of these spring cap bearings. It is to be noted that the aperture in the wall 11 is larger than the aperture in the adjacent spring cap and the spring cap 50 bearing on the buffer block is suitably shaped so that it may move freely within the aperture of the wall 11 and bear against the adjacent spring cap. To secure the buffing block and buffer housing in assembled relation the top and 55

bottom walls of the buffer block have suitably shaped apertures for reception of a bearing pin 29 which is disposed behind the rear spring cap in each spring housing and between the spaced 5 walls 14 of the housing.

Referring now to Figs. 1 and 2 of the drawing, it will be obvious that when buffing shocks are applied to the car they are taken up by the buffering block which moves inwardly of the car causing 10 spring cap bearing members 30 to move the associated spring caps 18 inwardly of the spring housings compressing the springs 32 between the spring caps since the inner spring caps bear against the wall 14 of the housings and cannot 15 move inwardly towards the car. When draft shocks are applied to the car, tending to pull the buffer block away from the car the bearing pins 29 bearing against the inner spring caps 17 compress the spring against the walls 11 of the spring 20 housings.

Having thus described the invention what I claim as new and desire to secure by Letters Patent is:

1. In a mine car buffer, in combination, horizontally spaced housing members each comprising spaced walls connected at one end by an end wall and having adjacent the other end of the spaced walls spaced apart opposing abutments, a member connecting said housings and extending 25 between and across the free ends of said other ends of said housing walls, a compression spring within each housing, bearing members at opposite ends of each spring engaging said abutments and said end wall respectively, a buffering block including a front face disposed across said spring housing end walls and top, bottom and side walls enclosing said spring housings, apertures in said housing end walls, abutments on the inner surface of said buffer block front face and registering within said housing end wall apertures, aligned apertures in said buffer block top and bottom walls at said spring housing abutments, and a removable member therein engaging a face of the adjacent spring bearing member.
- 45 2. In a mine car buffer, in combination, a buffering block having a buffering face and rearwardly extending top and bottom walls, a spring housing and buffering block supporting member comprising

a base portion for attachment to the mine car and spaced spring housings extending between said buffering block walls to adjacent the said buffering face thereof, each spring housing having upwardly disposed longitudinally spaced apertured 5 walls, a compression spring within each spring housing and between said apertured walls, abutments on the buffering block adjacent to and outwardly of each said apertured wall, said buffering block abutments moving through said spring 10 housing wall apertures to compress the contained springs as the buffering block moves in absorbing buffing and draft shocks.

3. In a mine car buffer, in combination, a car end sill member including outwardly extending 15 horizontally spaced spring housings, each housing including spring abutments spaced longitudinally of the car and outwardly of said end sill member, a compression spring within each housing and between said abutments, a draft and buffering block including a buffering face and rearwardly extending top and bottom walls enclosing and supported on said spring housings, said buffering block top and bottom walls extending rearwardly of the rearmost spring abutment of said 20 spring housings, means on said buffering face compressing said springs to absorb buffering shocks, and removable means supported by said buffering block top and bottom walls rearwardly of said springs for compressing said springs to absorb draft 25 shock imposed on the buffering block.

4. In a mine car buffer, in combination, a spring housing and buffering block supporting member, a buffering block mounted exteriorly of said supporting member, spring units supported 35 in said spring housings independently of said buffering block, fixed spaced independent spring unit engaging portions on said buffering block disposed at opposite ends of each of said spring units and movable relative to said supporting member for alternately and independently engaging opposite ends of said spring units whilst moving relative to said supporting housing under draft and buffering shocks, one of said spring engaging portions being detachable from said buffering block to permit assembly of the buffer.

HAROLD E. ABKOWITZ.
